CLAIM

The ornamental design for a tread of a tire, as shown and
described.

DESCRIPTION

FIG. 1 is a perspective view of the tire tread design of the
present invention, it being understood that the pattern is
repeated throughout the circumference of the tread; and,
FIG. 2 is an elevational view of the tire tread design shown
in FIG. 1.

The broken line showing of the tire inner bead and sidewall
in FIG. 1 is for illustrative purposes only and forms no part
of the claimed design.
